NATHAN W. O'BRYNE, OF BALDWIN, KANSAS

ELLIPSOGRAPH

Application filed January 4, 1932. Serial No. 584,657.

This invention relates to instruments for producing curved lines and particularly ellipses, and the primary object of the invention is to provide a structure known as an ellipsograph which may be used in scribing ellipses on any sheet of material, or which may be used for cutting mats, etching or cutting glass, or simply to apply a series of parallel ellipses upon a flat surface.

One of the primary objects of the instant invention is the contemplation of an ellipsograph that is extremely compact; comprises a minimum number of parts, yet performs the functions desired in a manner permitting flexibility as to size and position of the curved lines or ellipses produced.

Another object of the present invention is the provision of an ellipsograph that has a combination of parts to cause an action that is easily applied to any problem of describing an ellipse and that may be used commercially without encountering the customary requirements of setting and intricate adjustment.

Further and important objects of the invention will appear during the course of the following specification, referring to the accompanying drawing, wherein a preferred embodiment of the conception has been illustrated and wherein:

Figure 1 is a top plan view of an ellipsograph in position for use and embodying this invention.

Fig. 2 is a vertical, central section through the ellipsograph as it is illustrated in Fig. 1.

Fig. 3 is a side elevation of the same, and,

Fig. 4 is a plan view of the ellipsograph with certain parts thereof removed.

Similar reference characters are used to designate like parts throughout the several views of the drawing and the numeral 6 indicates a base having an annular upwardly extending flange 8 and a series of diametrically opposed indicator pointers 10 formed integrally therewith.

These pointers 10 are used to properly position the ellipsograph when bringing the same into use and, if desired, a number of spurs 12 may be associated with base 6 to preclude mal-

adjustment, after once locating the instrument.

To carry out one of the salient features of the invention, an internal gear 14 is mounted upon base 6 by engagement with flange 8, as illustrated in Fig. 2. Screws or analogous means 16 may augment this structure to preclude relative movement between base and internal gear 6 and 14 respectively. A pinion 18 is assembled with its teeth in mesh with the teeth of internal gear 14 and is rotatably supported by member 20 to permit its independent rotation as it is carried around the axis of internal gear 14 by crank lever 22.

Reference to Fig. 2 readily discloses that member 20 rotatably attaches pinion 18 to one end of crank lever 22 while pintle 24 pivotally affixes the other end of crank lever 22 to base 6 at the axis of internal gear 14. Members 20 and 24 may be of any suitable form, but in the instance shown, have been made to be shouldered and appropriately affixed in position so that there is no binding or false movements to preclude free action by the ellipsograph when it is being used. A bearing such as the ball 26 may be provided at the free end of crank lever 22 to assist in this aforementioned desirable free action, and means is likewise provided to steady the instrument as the marker thereof is carried through the path contemplated when the ellipsograph is set. A neck 28 should be rigidly associated with pinion 18 to stand thereabove on the axial line of pinion 18 so that knob 30 might be grasped by one hand of the operator. In the instance shown, neck 28 is bifurcated at its lower end to straddle member 20 and to present out-turned feet 32, through which may pass the fastening means 34 serving to assemble neck 28 and pinion 18.

Knob 30 is mounted for free rotation upon the upper end of neck 28, and if found appropriate, ball bearings 36 may be utilized at this point to lend free movement. A removable screw 38 may be used to maintain knob 30 in position.

In the drawing a marker 40 has been illustrated to be an ordinary pencil, but it is understood that in place of such a marker, a cutter knife or any other instrument might be used.

without altering the principal action of the ellipsograph. Marker 40 is attached to neck 28 through the intermediary of an arm 42. A transverse opening 44 is formed through neck 28 to receive arm 42 and a clamping screw 46 is set in position to intersect opening 44, whereby arm 42 may be clamped when the desired adjustment is reached.

Reference to Fig. 1 teaches that a series of graduated markings 47 may be inscribed upon the top of arm 42 to facilitate setting of the instrument. Arm 42 is jointed to allow vertical movement of marker 40 as the same is traveling through its elliptical path. This construction compensates for any irregularity which may be present on the surface of board or other material 48 upon which is being inscribed the ellipse illustrated by line 50 in Fig. 1. A cross pin 52 at the joint in arm 42 permits such movement and a set screw 54 is present to allow adjustment, replacement or substitution of marker 40.

The operation of the ellipsograph just described is obvious and it is but necessary to set down the fact that neck, arm and marker 28, 42 and 40 respectively move about the axis of pinion 18 when the pinion is independently rotated by grasping the upper end of marker 40. When pinion 18 is thus rotated about member 20, its engagement with internal gear 14 will immediately set up a driving action which carries the entire assembly just enumerated, pinion 18, and crank lever 22 about pintle 24 in a direction which is opposite to the direction of travel of marker 40. The arrows in Fig. 1 illustrate the above statement.

The pitch diameter of pinion 18 is just one-half the pitch diameter of internal gear 14 and one complete revolution on the part of pinion 18 will carry the same to a point diametrically opposite to the position illustrated in Fig. 1. In traveling to this point, marker 40 will be drawn progressively closer to the circumference of internal gear 14 and, it is obvious, it will be closest to internal gear 14 when pinion 18 has traveled one-quarter of the way around internal gear 14. Moving marker 40 once around internal gear 14 will cause pinion 18 to pass through its path of travel twice and thus an ellipse similar to that outlined by line 50 will be inscribed.

Arm 42 and marker 40 overhang the remaining parts of the ellipsograph and especially pinion 18, internal gear 14 and base 6, and the longitudinal adjustability on the part of arm 42 allows an ellipse of any size to be drawn; the limitation of such an ellipse as to its minor diameter being allowed by the distance between diametrically opposed pointers 10.

Manifestly, any number of arms 42 may be carried by neck 28 and when certain of said arms are desired to be left inoperative,

the outer portion of arm 42 may be swung about pin 52 so that marker 40 is not in position upon board 48. Unlike so many instruments of this character, it is possible to draw parallel ellipses and thus make elliptical borders or other decorative concentric or parallel ellipses wherever desired. The possibilities and flexibility of an ellipsograph embodying the features of this invention are unlimited. As an example, when it is desired to produce an ellipse with a major axis at right angles to the major axis of a previously described ellipse, it is but necessary to lift base 6 and set the pair of pointers 10 upon the major axial which were not on that line when the first ellipse was formed.

Having thus described the invention, what is claimed as new and desired to be secured by Letters Patent is:

1. In an ellipsograph, an internal gear; a pinion in mesh with said gear; a crank lever interconnecting said internal gear and pinion; and a marker carried by said pinion.

2. In an ellipsograph, an internal gear; a pinion in mesh with said gear; a crank lever having one end pivotally attached at the axis of said internal gear; and a marker carried by the pinion, said pinion being rotatably supported by the free end of said crank lever.

3. In an ellipsograph, an internal gear; a crank lever having one end pivotally attached at the axis of said internal gear; a pinion in mesh with said internal gear and rotatably supported by the other end of said crank lever; a neck rigid with said pinion; and an arm adjustably carried by the neck.

4. In an ellipsograph, an internal gear; a pinion in mesh with said gear; means mounting said pinion for independent rotation about its own axis and for travel in a concentric path around the axis of said internal gear; and a marker carried by said pinion.

5. In an ellipsograph, an internal gear; a pinion in mesh with said gear; means mounting said pinion for independent rotation about its own axis and for travel in a concentric path around the axis of said internal gear; an arm carried by said pinion; a marker on said arm; and structure forming a part of said arm to allow vertical movement of said marker as the same is guided around the internal gear by said arm.

6. In an ellipsograph, an internal gear; a pinion in mesh with said gear; means mounting said pinion for independent rotation about its own axis and for travel in a concentric path around the axis of said internal gear; a neck rigid with the pinion; an arm slidably mounted on the neck; and a marker carried by the arm.

7. In an ellipsograph, a base; an internal gear on the base; a crank lever pivotally attached at its one end to said base, at the axis of said internal gear; a pinion in mesh with the internal gear and rotatably supported at

the other end of said crank lever; and a marker overhanging said base and internal gear.

8. In an ellipsograph, a base; an internal gear on the base; a crank lever pivotally attached at its one end to said base, at the axis of said internal gear; a pinion in mesh with the internal gear and rotatably supported at the other end of said crank lever; an upstanding neck rigid with said pinion; a knob rotatably mounted on said neck; and a marker adjustably carried by said neck to overhang said base and internal gear.

In testimony whereof, I hereunto affix my signature.
